UNITED STATES PATENT OFFICE

EUGENE D. STIRLEN, OF NEW HAVEN, CONNECTICUT, ASSIGNOR TO THE STIRLEN ENGINEERING & RESEARCH CORPORATION, A CORPORATION OF CONNECTICUT

RECORDER FOR TRAFFIC SIGNAL SYSTEMS

Application filed August 20, 1928. Serial No. 300,935.

This invention relates to improvements in traffic signal systems, and more particularly to apparatus for recording the presence of vehicles which may pass a signal in violation 5 of traffic regulations.

Apparatus of this character is especially adapted for use at highway intersections where traffic is automatically controlled by electrically operated signals and the primary object of this invention is to provide a 10 recording apparatus which shall make a permanent record of the presence of any vehicle entering the street intersections when the right of way has not been given to the 15 vehicle.

Another object of this invention is to provide a recording apparatus of the character designated which shall make a permanent record of the time at which any vehicle shall 20 cause the actuation of the device.

A further object of the invention is to provide an apparatus of the character designated which may be associated with the usual type of electrically operated "go" and 25 "stop" signals operated by manual or automatically controlled mechanisms.

These and other objects of the invention will hereinafter appear in the accompanying specification and drawings, and specifically set forth in the claims.

In the drawings:

Figure 1 is a diagrammatic view showing a highway intersection employing a vehicle recording system embodying my invention; 35 Figure 2 is a plan view of the recording mechanism and the electrical wiring arrangement;

Figure 3 is a view partially in section showing a vehicle actuated means; and

40 Figure 4 is a view in elevation of a recording device.

Referring to Fig. 1 of the drawings, there is shown an electrically operated signal system arranged to indicate "stop" and "go" 45 signal lights at a street corner or intersection. The streets are indicated as north, south, east and west, and for the purpose of illustration, G' and R indicate green and red lamps visible on the north and south 50 streets, while G and R' indicate green and

red lamps visible on the east and west streets. These lights are connected in electric circuits so that lights G' and R' are energized simultaneously through one circuit and lights G and R are energized simultaneously through another circuit. 55

The energization of these circuits is controlled at the proper interval by an automatically operated timer mechanism of the well-known type, constructed and arranged 60 to energize the circuits for predetermined intervals of time and to prevent simultaneous operation of two signal lights on the same street. Associated with this timer mechanism is a recording mechanism connected in circuit so that it shall operate to 65 make a permanent record of impulses received during the indication of a certain signal. In the diagram shown, the recording mechanism is arranged to make a permanent record of any impulse received from 70 a street during the indication of the "stop" signal on that street. This is particularly advantageous in a case where a vehicle enters an intersection from a street having the 75 "stop" signal, and causes an accident. In such an occurrence, the record sheet may be examined to ascertain which vehicle violated the traffic signal.

In the illustrated embodiment of the invention, the recording mechanism is operated by means of suitable street switches indicated by numerals 2, 3, 4, and 5, and located in the respective streets so that they may be actuated by the passage of vehicles along 85 the street. These street devices are connected in circuit with wires 6, 7, and 8 by means of wires 9, 10, 11, 12, 13, 14, 15, and 16 respectively. The switches are all of a similar construction and a convenient form of street 90 switch is illustrated in Fig. 3 wherein one end of a bar 17 is pivotally mounted at 18 and the other end is yieldably supported by a spring 19. Adjacent to the movable end of the bar 17 are contacts 20 and 21 on wires 95 15 and 16, for example, and arranged to close the circuit in these wires when a passing vehicle presses the bar downward.

The signal lights are periodically energized through wires 6, 7, and 8 by means 100

of a timer mechanism 22 of a well known construction. This timer may be manual or automatic in operation and is connected to a convenient source of power indicated as 5 A. C. current.

A permanent record of the passage of a vehicle over a street device is made by a recording mechanism indicated by numeral 23 and shown in detail in Figs. 2 and 4. 10 This mechanism comprises a base member 24 upon which are mounted electro-magnets 25 and 26 having armatures 27 and 28 respectively. Armature 27 is mounted in a standard 29 by pivot 30 and armature 28 15 is likewise pivotally mounted in a standard 31 by pivot 32. An adjustable stop 33 is provided to regulate the movements of the armatures, which are yieldably held by means of tension springs 34 and 35 respectively. Each of the armatures 27 and 28 20 is provided with a cutting point 36 or 37, respectively, for piercing a record sheet 38, which is moved progressively under the cutting points.

25 The record sheet for receiving the permanent record is shown in the form of a paper strip which is fed across a table 39 provided with apertures 40 and 41 over which the paper passes and through which the cutting members project when actuated by the respective armatures.

In order to give definite identification, 30 a square perforation 40 in the strip shall indicate an impulse from the street switches in the east and west street, and a round perforation 50 on the other side of the strip shall indicate an impulse from the north and south street. To further provide for 35 definite identification, the strip is marked off in time indications of hours and minutes, so that the time at which a perforation is made shall be shown by the strip and thus a permanent record of the impulse is made.

40 The mechanism for operating the strip 45 includes transfer rolls 42 and 43. The strip is slowly fed from the supply roll 42 to the winding roll 43 by means of a motor 44, which may be in the form of a clock mechanism arranged to operate the rolls at a desired speed in accordance with the time 50 indications on the strip. While there is shown and described a strip transferring mechanism, it is obvious that a cardboard disc may be employed to receive the permanent record.

55 The magnets for operating the strip perforators 36 and 37 are each connected in a different signal lamp circuit so that the magnets may only be energized when circuits are completed to the respective stop lights. As shown, magnet 26 is connected in series with wire 10 through lead wires 45 and 46, and is thereby energized when the circuit is closed by either of street switches 60 2 or 4, during the time in which power is

supplied to wires 7 and 8. In a like manner, magnet 25 is connected in series with wire 12 by lead wires 47 and 48, and is thereby energized when the circuit is closed by either of street switches 3 or 5 during the time 70 in which power is supplied to wires 6 and 7.

Having thus described a preferred embodiment of the invention, the operation thereof is carried out in the following manner. For the purpose of illustration, lights 75 G, G indicate "go" on the east and west street and the lights R, R indicate "stop" on the north and south street, and these lights are energized by wires 6 and 7. A vehicle passing over the street switches 3 or 5 in the 80 north and south street closes the circuit and energizes magnet 25, thereby actuating armature 27, and causing a perforate record on the paper strip. The tape being thus perforated on one of the time graduations, 85 the time at which the impulse occurred may readily be noted. Since the magnet 25 can only be energized when the stop light is exhibited on the north and south street, it is evident that the vehicle causing the impulse 90 proceeded over the street device in violation of the signal, and may, therefore, be presumed to be at fault should an accident occur on the street intersection. In a similar 95 manner, when the signal lights are periodically reversed on the intersecting street so that the "stop" signal is shown on the east and west street, magnet 26 may only be energized to make a permanent record of any 100 vehicles passing over the street switches in these streets.

A recording mechanism embodying the present invention, therefore, makes and preserves an individual and permanent record of the time at which each separate vehicle 105 causes an impulse by crossing one of the street devices in violation of an indicated traffic signal.

Having thus described a preferred embodiment of the invention, it is obvious that 110 various changes may be made therein without departing from the scope of the invention as set forth in the claims.

I claim:

1. In an apparatus of the character described and to be installed at the point of intersection of two vehicle lanes, said apparatus including signalling means, and means for operating said signalling means to accord right of way over said vehicle lanes, recording means connected to said operating means, and means associated with said lanes and responsive to the passage of a vehicle over the same, said last named means being connected to said recording means to operate the latter when said signalling means is in a predetermined condition. 115

2. A signalling apparatus to be installed at the point of intersection of two vehicle 120

lanes and at which point signalling means is provided, and which signalling means is connected to operating means so that right of way may be accorded to vehicles moving over said vehicle lanes, said apparatus including a vehicle actuated control in one of said lanes, a recording means connected to said control and to said operating means, said recording means functioning in response to the passage of a vehicle along one of said lanes and past said control when said operating and signalling means are in predetermined conditions.

3. A signalling apparatus to be installed at the point of intersection of two vehicle lanes and at which point signalling means is provided, and which signalling means is connected to operating means so that right of way may be accorded to vehicles moving over said vehicle lanes, said apparatus including vehicle actuated controls in each of said lanes, recording means connected to said controls, and means connecting said operating means to said recording means whereby to cause the latter to operate in response to functionings of said controls and when said operating and signalling means are in predetermined condition.

4. A signalling apparatus to be installed at the point of intersection of two vehicle lanes and at which point signalling means is provided, and which signalling means is connected to operating means so that right of way may be accorded to vehicles moving over said vehicle lanes, said apparatus including vehicle actuated controls in each of said lanes, recording means connected to said controls, and means connecting said operating means to said recording means whereby to cause the latter to operate in response to functionings of vehicle actuated controls of the lane in which right of way is interrupted by said signalling means.

5. A signalling apparatus to be installed at the point of intersection of two vehicle lanes and at which point signalling means is provided, and which signalling means is connected to operating means so that right of way may be accorded to vehicles moving over said vehicle lanes, said apparatus including means functioning when said signalling means is operating in a predetermined manner to record the passage of a vehicle into the intersection, said signaling means being unaffected by the operation of said recording means.

In testimony whereof I affix my signature.
EUGENE D. STIRLEN.
